Attys.

UNITED STATES PATENT OFFICE.

GEORGE H. GILMAN, OF CLAREMONT, NEW HAMPSHIRE, ASSIGNOR TO SULLIVAN MACHINERY COMPANY, OF BOSTON, MASSACHUSETTS, A CORPORATION OF MASSACHUSETTS.

PRESSURE-FLUID TOOL.

1,409,703.

Specification of Letters Patent. Patented Mar. 14, 1922.

Application filed November 13, 1914. Serial No. 871,908.

To all whom it may concern:

Be it known that I, GEORGE H. GILMAN, a citizen of the United States, and a resident of Claremont, Sullivan County, New Hampshire, have invented an Improvement in Pressure-Fluid Tools, of which the following description, in connection with the accompanying drawings, is a specification, like characters on the drawings representing like parts.

This invention relates to tool actuating apparatus, and is more especially concerned with a pressure fluid apparatus having special application to rock drilling and mining purposes.

The object of my invention is to provide an improved drilling apparatus, and more particularly to provide an improved hand-portable percussive rock drill of a type adapted for universal use, i. e., as a hand tool, with a shell and cradle mounting, with suitable pneumatic or other feeding means for stopping, etc.; in other words to provide an improved drill adapted for use in any of the well known methods of drilling to which hand-portable tools are applied.

My invention will be best understood by reference to the following specification, when taken in connection with the accompanying drawings of one specific embodiment thereof, while its scope will be pointed out in the appended claims.

In the drawings:

Fig. 1 is a plan of a pressure fluid tool shown partially in horizontal section;

Fig. 2 is a sectional view, partly in elevation, on line 2—2 of Fig. 1; and

Fig. 3 is a cross sectional view on line 3—3 of Fig. 2, looking toward the left.

Referring to the drawings, and to the embodiment of my invention which I have selected for illustration, I have there shown tool percussion means comprising a cylinder 4, in which a piston 5 is mounted to reciprocate, which piston is controlled in its reciprocations by a pressure fluid operated distributing valve 6, similar to that forming the subject matter of United States Letters Patent, No. 627,703, to Thomas Officer, dated June 27, 1899, wherein there is shown a distributing valve having a central spool which controls the admission of pressure fluid to, and the exhaust from, opposite ends of the cylinder alternately, and wherein the valve is in turn reciprocated by pressure

fluid under the control of the piston itself, the valve for this purpose being provided with two end spools, against which the pressure fluid acts to throw the valve.

Referring to Fig. 2 of the accompanying drawings, the valve chest is provided with a pressure fluid intake 7, from which pressure fluid flows into an annular port 8 in a valve block or bushing, the latter herein comprising two independent sections 9 and 10, mounted in a valve chest 11. Cushioning springs 12 and 13, bearing against the valve bushing sections 9 and 10 respectively, are held in place and suitably tensioned by a pair of tie rods 14 extending through the springs and through the valve chest.

The distributing valve, when reciprocated in the normal operation of the machine, causes pressure fluid to be supplied from the port 8 alternately to cylinder ports 15 and 16 leading to the front and rear ends, respectively, of the cylinder 4, whereby the piston 5 is reciprocated in a wellknown manner. Under some circumstances, it may be desirable to withhold effective power supply from the cylinder, or at least one end thereof, in order to discontinue temporarily the operation of the tool percussion motor, and maintain the piston adjacent one end of its stroke. To this end, I have herein provided means for manually controlling the operation of the distributing valve 6, such means herein comprising a pin or plug 17, constituting what may be termed a push button having an enlarged portion 18, mounted to slide in a recess 19 provided in a boss 20, formed on and projecting inwardly from a bushing 21, interposed between the spring 12 and the valve bushing section 9. The reduced portion 17 extends rearwardly through the spring 12 to a point where it may be conveniently engaged by the thumb of the operator and pushed inwardly. The inner end of the push button is provided with a reduced portion 22, which extends through the axially perforated end of the boss 20 to a point where it may engage the adjacent end of the valve 6, whereby the latter may be manually thrown to one end of its stroke and held there, thus causing pressure fluid to be supplied to the rear end of the cylinder, and the piston thereby held adjacent the forward end of the stroke, while the pressure on the push button is continued. As a means for preventing the

formation of an air cushion in the chamber 19, which might prevent the push button from being pushed forward, its enlarged portion 18 is herein provided with a longitudinal groove 23, constituting a vent.

The described tool percussion motor may percussively actuate a suitable tool for the character of the work to be performed, such for example as a drill-steel 24. This drill-
10 steel might be directly connected to the piston to be reciprocated thereby, as is customary in one general type of rock drills, but for the purpose of the present invention, I have shown a tool of the hammer type, in
15 which the drill-steel is provided with a polygonal shank 25 mounted in a chuck 26, and adapted to be struck by the piston, the latter for that purpose being herein provided with a piston extension or hammer bar
20 27. This hammer bar extends from the cylinder proper into an axial bore 28 in the elongated front cylinder head 29, and there is thus formed at the rear end of the drill-steel a chamber 30.
25 The chuck 26 is herein in the form of a sleeve mounted to rotate in the elongated front cylinder head, and held against axial motion by front and rear shoulders 31 and 32 respectively, against which its front and
30 rear ends abut. For convenience in assembling the parts, the front cylinder head 29 is provided with a removable front section 33, secured to the rear section by bolts 34.

I may employ any appropriate type of
35 tool rotating motor, but for the purpose of illustration, I have selected a wellknown type of pressure fluid motor commercially known as the spiro-motor, comprising a pair of double helical, or herringbone rotors 35,
40 which are nothing more nor less than double helical, or herringbone gears, to which pressure fluid is applied at a port 36 midway between their ends. It is well known that in percussive tools there is great vibration and
45 shock caused by the unbalancing action of the reciprocatory percussive piston. This vibration and shock tends to rapidly wear out moving parts of the apparatus which work in planes substantially transverse to the line of piston travel. In supplying a rotary motor to operate the drill steel, whether one or a plurality of rotors be employed, the efficiency of the motor depends on the close fit between the rotating means and the housing.
50 In the apparatus illustrated I have overcome the tendency of the vibration to produce undue wear between the rotating means and the housing by arranging the axis of the rotating means typified by the rotors 35 in the same direction as the axis of the piston 27. The pressure fluid, on being admitted through the port 36 to the pocket or space at the center of the gears formed by the teeth of the latter, rotates the gears in
55 the direction of the arrows (Fig. 1), and

passing along the teeth of the gears toward the ends of the latter, is exhausted, when the teeth forming the pockets run out of mesh, into a chamber 37 at the front end of the gears, and chambers 38 at their rear ends. 70 These chambers might very well exhaust directly into the atmosphere if desired, but I prefer to conduct the exhaust through a port 39 into the chamber 30. A port 40, leading from this chamber directly to the atmosphere, 75 permits the exhaust to be conducted directly to the atmosphere if desired, or may be closed by the thumb or finger of the operator. If a solid drill-steel be employed, the port 40 will naturally be allowed to remain open to permit the free escape of the exhaust; but if the drill-steel be provided with a passage, such for example as the axial perforation 41, the exhaust fluid may be conducted to the work for the purpose of 80 blowing away the cuttings. In the latter case, the port 40 may still be allowed to remain open, if it should be found that the perforation in the drill-steel is not sufficient to carry away the exhaust without undue 85 back pressure. If the cuttings present an undue obstruction to the action of the drill-steel, the port 40 may be closed by the thumb or finger of the operator, and the entire exhaust compelled to flow into the 90 drilled hole. It will now be apparent that there is provided means available for conducting some or all of the exhaust pressure fluid from the tool rotating motor to the work, and means for conducting some or all 95 of the exhaust pressure fluid from the tool rotating motor by another course to the atmosphere.

As a means for throttling or entirely shutting off the supply of pressure fluid to the tool rotating motor, I have herein provided a valve 42, threaded into the front cylinder head and controlling the pressure supply passage 43 leading from the port 8 to the port 36. This valve is herein provided with a suitable handle 44, whereby it may be conveniently turned for the purposes of adjustment, and is provided with a locknut 45, engaged by a spring-pressed pin 46, whereby the valve may be held in the desired position of adjustment, without danger of such adjustment being deranged by reason of the vibration to which it is subjected when in operation.

It will now be apparent that I have provided means for controlling the tool percussion means and tool rotating means, and for causing either to operate to the exclusion of the other. In other words, I have provided means at will to withhold effective 120 power supply from either motor, while still continuing to supply the other, and whereby the operation of the tool percussion motor may be discontinued and the operation of the tool rotating motor regulated, or alto- 125 130

gether discontinued, these functions being accomplished by the use of the push button 17 and valve 42.

The tool rotating motor may be connected 5 to the tool chuck by any suitable means to rotate the latter, but I have herein shown the chuck provided with a pair of spline-ways 47 to receive keys 48 carried by a worm gear 49, through which the chuck extends. 10 This worm gear meshes with a worm 50, herein formed on a worm shaft 51, on which is also formed a pair of beveled bears 52, meshing with and driven by beveled pinions 53, formed integral with the rotors 35. By 15 this means, a great reduction in speed is obtained, and the rotation of the drill-steel is accomplished independently of the operation of the tool percussion motor.

In the normal operation of the tool, the 20 piston is reciprocated, and delivers a rapid and continuous succession of blows on the inner end of the drill-steel, while the latter is rotated, and its cutting edges continually turned and presented at fresh points of engagement with the rock, the speed of the rotation being variable by means of the valve 42. In case it becomes necessary to rotate the drill steel without having the piston reciprocate in its cylinder, it is necessary 25 merely to push forward the push button at the rear end of the valve, in order that the distributing valve will be held in its extreme forward position. With the usual main throttle in its open position, this action will cause the piston to be thrown forward against or adjacent the drill steel, and held there by the live pressure fluid which will be admitted to the rear end of the cylinder; but at the same time, pressure fluid 30 will be admitted to the tool rotating motor. 40

Under some circumstances, it may be desirable to take a supply of pressure fluid from the cylinder 4 to the chamber 30 to be conducted to the hole being drilled, and for 45 this purpose, I have herein shown the piston extension or hammer bar as being provided with a longitudinal groove 54, which at each stroke of the piston enters into the front end of the cylinder, and conducts pressure fluid 50 therefrom to the chamber 30, from whence it passes into the hollow drill-steel. This groove, however, may be omitted, if desired.

While I have herein shown and described one specific embodiment of my invention, 55 and have disclosed and discussed in detail the construction and arrangement incidental to one specific application thereof, it is to be understood that the invention is limited neither to the mere details or relative arrangement of parts, nor to its specific embodiment herein shown, but that extensive deviations from the illustrated form or embodiment of the invention may be made, 60 without departing from the principles 65 thereof.

Having thus described my invention, what I claim and desire by Letters Patent to procure is:—

1. A hand-portable percussive rock drill of a type adapted for universal use comprising, 70 in combination, a casing, a drill steel, a chuck by which said drill steel is carried, said chuck being rotatably mounted in said casing, a fluid pressure percussive motor in said casing comprising a cylinder and a piston therein cooperating with said drill steel, a fluid pressure steel rotating motor carried by said casing and comprising a plurality of rotors having their axes parallel to the axis of said cylinder and piston, and gearing 75 connecting said rotating motor and chuck.

2. A hand-portable percussive rock drill of a type adapted for universal use comprising, 80 in combination, a casing, a hollow drill steel, a chuck by which said drill steel is carried, said chuck being rotatably mounted in said casing, a fluid pressure percussive motor in said casing comprising a cylinder and a piston therein cooperating with said drill steel, a fluid pressure steel rotating 85 motor disposed within the outlines of said casing and comprising a plurality of rotors having their axes parallel to the axis of said cylinder and piston, a gear carried by at least one of said rotors, a gear associated 90 with said chuck, speed reducing transmission devices connecting said gears, and means for transmitting exhaust fluid from said steel rotating motor to said hollow steel carried in said chuck. 100

3. A percussive rock drill comprising, in combination, a casing, a drill steel, a chuck by which said drill steel is carried, said chuck being rotatably mounted in said casing, a fluid pressure percussive motor in said 105 casing comprising a cylinder and a piston therein cooperating with said drill steel, a fluid pressure steel rotating motor in said casing and comprising a plurality of rotors having their axes parallel to the axis of said cylinder and piston, said rotating motor being operatively connected with said chuck, and separate devices for independently controlling the supply of pressure fluid to said 110 percussive motor and rotating motor respectively. 115

4. A percussive rock drill comprising, in combination, a hollow drill steel, a percussive motor cooperating therewith, means for controlling said percussive motor, a fluid pressure steel rotating motor, and means independent of said percussive motor controlling means for controlling the exhaust of said rotating motor to cause a greater or less amount thereof to be discharged through 120 said hollow drill steel or directly to the atmosphere. 125

5. In a hand-portable percussive rock drill of a type adapted for universal use, the combination comprising means for simul- 130

taneously rotating and hammering upon a
5 drill steel comprising a drill steel rotating
motor having intermeshing rotors rotatable
on longitudinally disposed axes, a cylinder
in alinement with which a drill steel is
adapted to be arranged, a percussive piston
10 in said cylinder, a fluid pressure supply re-
ceiving chamber, and means for supplying
fluid to said rotation motor and to said cyl-
15 inder comprising passages connecting said
chamber with said steel rotating motor and
with said cylinder, a valve extending trans-
versely of said chamber for controlling the
20 motive fluid supply from the chamber to the
cylinder, and a second valve communicating
with the chamber for controlling the motive
fluid supply to the rotation motor.

6. A hand-portable percussive rock drill
25 of a type adapted for universal use comprising,
in combination, a percussive piston pro-
vided with a striking portion of less diam-
eter, a casing having a cylinder formed
30 therein in which said piston is reciprocable,
a reduced hollow portion adjacent said cyl-
35 inder in which said striking portion recip-
rocates, and a recess adjacent said reduced
portion, a chuck in said casing in communi-
cation with said reduced hollow portion, a
40 motor comprising a plurality of rotors in
said recess, said recess being in communica-
tion with said reduced hollow portion ad-
jacent said chuck, said rotors having their
45 axes parallel to the axis of said cylinder,
and means between said chuck and motor
whereby the former may be rotated by the
latter.

7. A hand-portable percussive rock drill
40 of a type adapted for universal use comprising,
in combination, a casing having a
cylinder therein, a bore of reduced diameter
communicating with said cylinder, and a
chamber adjacent said reduced portion, a piston
45 reciprocable in said cylinder and having a
portion of reduced diameter reciprocable
in said bore, a chuck in said casing, a recess
to the rear of said chuck into which a drill
steel may project when in operative position,
50 a motor having intermeshing rotors rotatable
on axes parallel to the bore of said

cylinder and located in said chamber, means
50 for supplying operating fluid to said cylinder
and to said motor, and means constituting
an operative driving connection between
said motor and said chuck.

8. A hand-portable percussive rock drill
55 of a type adapted for universal use comprising,
in combination, a casing having a cylin-
der therein, a bore of reduced diameter com-
municating with said cylinder, and a cham-
ber adjacent said reduced portion, a piston
60 reciprocable in said cylinder and having a
portion of reduced diameter reciprocable in
said bore, a chuck in said casing, a recess to
the rear of said chuck into which a drill steel
may project when in operative position, said
65 recess being in communication with said
chamber and having means whereby a vari-
able communication with the atmosphere
may be provided, a motor having intermesh-
70 ing rotors rotatable in said chamber, means
for supplying operating fluid to said cylin-
der and to said motor, and means constituting
an operative driving connection between
said motor and said chuck.

9. A hand-portable percussive rock drill
75 of a type adapted for universal use comprising,
in combination, a casing having an en-
larged cylinder therein, a reduced hollow
portion adjacent said cylinder, and a cham-
ber adjacent said reduced portion and at
80 one end of and partially in front of said
cylinder, a piston reciprocable in said cylin-
der and provided with a portion recipro-
cable in said reduced portion, a chuck in said
casing, a plural rotor motor rotatable on lon-
85 gitudinally disposed axes and located in said
recess, and means therebetween for rotating
said chuck by said motor, the forward end
of said casing forming a bearing for the
90 chuck and a casing for said last named
means.

In testimony whereof, I have signed my
name to this specification, in the presence of
two subscribing witnesses.

GEORGE H. GILMAN.
